(57) **CLAIM**

The ornamental design for a tub grip, as shown and described.

DESCRIPTION

FIG. 1 is a prospective view of our new design for a tub grip. FIG. 2 is a top plan view.

FIG. 3 is a bottom plan view.

FIG. 4 is a right side elevation view.

FIG. 5 is a rear elevation view.

FIG. 6 is a left side elevation view; and, FIG. 7 is a front elevation view.

The broken line showing of portions of the attachment is for illustrative purposes only and forms no part of the claimed design.
